UNITED STATES PATENT OFFICE

2,032,991

FOUNTAIN PEN AND METHOD OF MAKING

Walter Lange, Berlin-Schlachtensee, Germany,
assignor to General Electric Company, a corporation of New York

Application September 26, 1932, Serial No. 634,975
In Germany September 30, 1931

5 Claims. (Cl. 113—32)

My invention relates to fountain pens and methods for making them and concerns particularly pens for use with recording instruments.

It is an object of my invention to produce a pen which may easily be manufactured at slight cost and which is not easily damaged.

Another object is to produce a pen from which the ink flows with sufficient rapidity to produce a clear legible record and to avoid faulty indications. Still another object is to produce a pen having a large supply of ink in the capillary space.

A further object of my invention is to produce a pen which may easily be cleaned even after the ink has dried. Other and further objects and advantages will become apparent as the description proceeds.

In accordance with my invention in its preferred form, a relatively short piece of cylindrical tubing is utilized to form the pen. The lower portion of the tubing is flattened and trimmed to form a pair of parallel nibs between which a capillary space is formed. The unflattened portion of the tube serves as the ink reservoir. Preferably, the flattened portion of the tube is trimmed to provide nibs having V-shaped edges. The point of the V which is at the lowermost portion of the pen is the portion which comes in contact with the record strip and from which the ink flows. Obviously, a pen of this type is preferably utilized in connection with apparatus which permits the axis of the cylindrical portion of the pen to remain substantially vertical. The pen is attached to a pen arm of any suitable construction, preferably the upper end of the cylindrical portion being fastened to the end of the pen arm. The features of my invention which I believe to be novel and patentable will be pointed out in the claims appended hereto.

To afford a better understanding of my invention, reference is made in the following description to the accompanying drawing in which Fig. 1 represents in perspective an assembled pen arm and pen forming one embodiment of my invention; Fig. 2 represents a piece of tubing forming the first step in the manufacture of pens in accordance with my invention; Fig. 3 illustrates a further step in the manufacture; and Fig. 4 represents the pen alone and illustrates the final step in the manufacture of the pen.

Referring now more in detail to the drawing in which like reference characters refer to like parts throughout, I utilize an arm 11 having a pen 12 attached at the end thereof. Pen 12 has a tubular portion 13 preferably cylindrical in

shape. At the lower end of the tubular portion 13 are two flat nibs 14 and 15 preferably having V-shaped edges. The nibs 14 and 15 are supported a sufficient distance apart to form a capillary space 16 between them which communicates with the reservoir formed by the space within the tubular portion 13. The pen 12 may be attached to the pen arm 11 by forming a union between the upper edge of the tubular portion 13 and the lower surface of the end of the pen arm 11. A suitable opening 16' is provided in the end of the pen arm 11 to permit introducing ink into the pen 12. The opening may, if desired, be semi-circular in shape or have some other suitable shape to permit pouring ink into the pen and still to prevent ink from being spilled from the pen in case the pen should be tipped. The arrangement shown would be suitable for operations in which the pen was caused to drop considerably below the level of the pins 11' which form a pivot for the pen arm 11, to permit the pen to remain in contact with a record strip. The opening 16' may, if desired, be arranged to come entirely at the side of the pen axis toward the pins 11' so that the pen may, if desired, be caused to operate with the pen arm 11 substantially vertical and the axis of the pen substantially horizontal.

Any suitable method may be employed for producing pens of the character described but I have found that they may be manufactured quickly, easily and at small expense in the following manner: A relatively short piece of tubing 17, shown in Fig. 2, is utilized as the starting point in the manufacture of the pen. A bar 18 conforming in cross-section to the inner portion of the tubing 17 but having a rounded end 18' is inserted into the piece of tubing 17. The lower end 17' of the tube 17 is then flattened in any suitable manner as by pressing the tube between suitable dies, and the bar 18 is withdrawn. The flattened portion 17' is then cut preferably with V-shaped edges to form the nibs 14 and 15. Obviously, flattening and trimming might be performed in a single operation if suitable dies were employed.

The point 19 formed by the intersection of the edges 20 and 21 forms the pen point which comes in contact with the record strip. Owing to the large surface of the nibs 14 and 15, a relatively large capillary space is formed and there is an ample supply of ink within the capillary space to permit the ink to flow rapidly from the point 19 to the record strip when the arm 11 is quickly deflected through a large angle. Consequently,

sufficient ink flows from the pen to form a clear and legible record at every point of the record strip which has been traversed by the pen point. The space within the tubular portion 13 of the pen 12 forms a reservoir of ample size to permit operation of a recording instrument for a considerable period of time without replenishing the supply of ink in the reservoir. The pen may be cleaned easily by inserting a thin plate between the nibs 14 and 15.

In accordance with the provisions of the patent statutes I have described the principle of operation of my invention, together with the apparatus which I now consider to represent the best embodiment therefor, but I desire to have it understood that the apparatus shown is only illustrative and that the invention may be carried out by other means.

What I claim as new and desire to secure by Letters Patent of the United States, is:

1. The method of producing a fountain pen which comprises inserting a bar having a rounded end into a tube having an internal cross-section conforming substantially to the cross-section of said bar, flattening the portion of said tube beyond said bar, withdrawing said bar and trimming the flattened end of said tube to form two parallel nibs of the pen.

2. A pen for a recording instrument comprising a tube serving as a reservoir for ink, and a

pair of flat nibs pressed from said tube at one end thereof and spaced to form a capillary space therebetween communicating with said reservoir.

3. A pen for a recording instrument comprising a tube serving as a reservoir for ink and a pair of flat nibs pressed from said tube at one end thereof, said nibs having V-shaped edges and being spaced to form a capillary space therebetween communicating with said reservoir.

4. In combination with a recording instrument, a substantially horizontal pen arm and a pen attached at the end thereof, said pen comprising a tube having its axis substantially vertical and serving as a reservoir for ink, and a pair of flat nibs pressed from said tube at the lower end thereof, said nibs being spaced to form a capillary space therebetween communicating with said reservoir.

5. The method of producing a fountain pen which comprises inserting a bar having a rounded end into a tube having an internal cross-section conforming substantially to the cross-section of said bar, flattening the portion of said tube beyond said bar and simultaneously trimming the flattened end of said tube to form parallel nibs of the pen, and withdrawing said bar.

WALTER LANGE.
